VAPOR GENERATOR

Forrest G. Raynor, Baldwin, N. Y., assignor to The Babcock & Wilcox Company, New York, N. Y., a corporation of New Jersey

Application March 25, 1954, Serial No. 418,661

5 Claims. (Cl. 122—408)

This invention relates to fluid heat exchange apparatus, and the invention is considered as exemplified in a vapor generating unit of high capacity.

Many modern vapor generating units operate at high fluid pressures of the order of 1500-2500 p. s. i. and it is evident that these units, in order to withstand such pressures over a long life, must have their pressure components of considerable wall thickness. This is particularly true of the vapor and liquid drums of the pertinent units. Some of these drums have a length of the order of 50-60 feet and a diameter of the order of 4-6 feet. Under such conditions, the wall thickness of the steel drum wall must be great. It is, in many cases, of the order of 6-10 inches, and, in some cases, some sections of the drums are of much greater wall thickness. This is particularly true in the drum zone in which downcomers are connected to the liquid space of the drum. In order that the drums of the pertinent units may effectively operate over a long period, considerable attention must be paid to the metal stresses in the drums. In many cases the drums are subject to pre-stressing in their fabrication in order that the operative stresses due to fluid pressures of normal operation may be of an optimum character.

In the manufacture of any such drums, it is obviously important that the many downcomer tubes and riser tubes connected to the drum must be joined therewith in pressure-tight condition. This involves contact of the connected tubes and the drum metal over large areas and it involves stressing of the drum metal.

All of the above conditions must be taken into consideration in the starting up of a large capacity vapor generating unit, and particular attention must be paid to the method of starting up the unit in order that additional and undesired stresses in the drum metal may be avoided. To attain this end the starting up of such a unit must begin with a low heat input and the increments of heat input must be small and they must be effective over considerable periods of time in order that the temperature gradients in the metal, and particularly the drum metal, may be kept within allowable limits. For these reasons, complicated and extensive time-temperature schedules must be carefully followed in the starting up of the unit.

This invention deals with a unit to be started up under the above conditions, and more particularly, with a unit in which there is a row of downcomer tubes leading from the bottom of the drum along its straight section. In many such units the drum ends, with their dished or convex end portions, must project substantially beyond the zone of the downcomers and this arrangement leaves a considerable body of liquid within each of the pertinent end portions and disposed to one side of the main stream of liquid entering the end downcomers. Therefore, the increase in liquid temperature involved in the starting up of the unit is not uniform. The attendant heat input is less effective in the bodies of the liquid at the drum ends than in the zone immediately adjacent

2

the downcomers. This invention involves fluid flow directing means so associated with the end downcomers and the drum ends so as to overcome the pertinent difficulty and maintain substantially constant temperatures in the drum metal during starting up.

5 The invention is concisely set forth in the appended claims, but for a clearer understanding of the invention, its uses and advantages, recourse should be had to the accompanying description which refers, by like reference characters, to the accompanying drawing in which a preferred embodiment of the invention is illustrated.

In the drawings:

Fig. 1 is a side sectional view indicating a type of high pressure vapor generating unit to which the invention applies;

15 Fig. 2 is a transverse vertical section of the vapor and liquid drum of the pertinent vapor generating unit;

Fig. 3 is a partial vertical section through the Fig. 2 drum showing the illustrative liquid flow directing means leading from the drum end portion to the inlets of the 20 adjacent downcomers; and

Fig. 4 is a plan section of one end of the drum, on the section line 4—4 of Fig. 2.

The invention is applicable to the vapor and liquid 25 separating drum 10 of the Fig. 1 high pressure vapor generating unit. This unit includes a vertically elongated combustion chamber 12 defined by upright vapor generating wall tubes, some of which are indicated at 14 as leading from bottom header 16 to the top header 18. The fluid flows continue thence through roof tubes

30 20 to the vapor and liquid inlet chamber 22 of the drum 10. Along the opposite wall of the combustion chamber other vapor generating tubes 24 lead upwardly from the lower headers 26 and 28. These tubes have intermediate portions 30 upwardly inclined toward the rear wall 32 of the convection gas pass 34. Beyond the upper ends of these inclined portions the tubes are bent to form a tubular screen 36 disposed across the gas inlet of the gas pass 34. Beyond the upper portion of this screen the tubes are disposed in alignment to define the rear wall 38 of the combustion chamber. These tubes are risers having their upper parts 40 connected to the vapor and liquid mixture inlet chamber 22 of the drum.

35 The remaining walls of the combustion chamber are similarly defined by upright vapor generating tubes connected by appropriate headers and other connections to the vapor and liquid mixture chamber 22. There may be, at the opposite side of the drum 10, a similar vapor and liquid mixture chamber 42 connected with the mixture chamber 22 by inverted channel connections, such as 44, which, throughout a substantial part of the length of the drum, are disposed between the downcomers 46-48, as indicated in Fig. 3.

40 Fig. 2 indicates vapor and liquid separators 50 having whirl chambers having substantially tangential inlets communicating with the upper parts of the vapor and liquid mixture chambers 22 and 42, respectively. There would preferably be a row of such separators at each side of the drum, the separators of one row communicating with the chamber 22 and those of the other row communicating with the chamber 42. These vapor and liquid separators are preferably of the type illustrated by the disclosure of the Fletcher and Rowand Patent 2,289,970 of July 14, 1942. Each separator discharges separated liquid downwardly into the drum space between the chambers 22 and 42 where a normal water level is maintained as at 54. Separated vapor is discharged from the tops of the separators and subsequently passes from the drum vapor space through circulators 56 to a superheater which may include the banks of tubes such as those indicated at 58 and 60, in the up-

45 50 55 60 65 70

flow gas pass 34 of the vapor generator. Downcomers 46-48 and 62-64 are indicative of a row of downcomers communicating with the water space of the drum 10 and leading downwardly along the rear wall of a gas pass 34 to headers 26-28.

As indicated in Figs. 3 and 4 the endmost downcomers are considerably spaced from the adjacent end of the drum. This is a situation in which there will be a large body of liquid disposed within each of the drum ends and beyond the zone immediately adjacent the inlets of the downcomers. This situation causes a liquid temperature difference between the liquid in the drum ends and the main body of liquid immediately adjacent the inlets of the downcomers which would promote undesirable metal stresses in adjacent portions of the drum when the vapor generating unit is being started up, and such thermally created stresses are apt to be particularly damaging in the vapor and liquid drums of vapor generating units operating at very high pressures and temperatures. Under such conditions the thickness of the drum walls may range anywhere from 4-6" to 15", and the undesirable effects of these pertinent stresses increase as the thickness of the drum metal increases. These undesirable effects may also be augmented by the welded construction of the drums. To prevent these undesirable stress effects the applicant provides flow directing means such as the inverted channel or tunnel member 66 at each end of the drum. The inlet 68 of this member is in direct communication with the inlets of one or more of the end downcomers, such as 62-64. Fig. 3 indicates the outlet end of the channel member 66 as having a closure 72. Thus, the liquid within the drum and adjacent the drum ends will circulate freely with the remaining body of the circulating liquid and the metal temperatures at the drum ends will be maintained at substantially the same value as the temperature of the other parts of the drum. The members 66 may also be considered as a part of conduit means of a tubular nature establishing separate fluid flows from the drum ends to the downcomers.

The conduit means including the members 66 have a free flow area greater than that of the downcomers directly associated therewith. As to the further details relative to the pertinent type of vapor generating and superheating unit, it is indicated that this unit is intended to be more of the type shown in detail in the common assignee's pending application Ser. No. 291,686, filed June 4, 1952.

What is claimed is:

1. In a natural circulation vapor generating unit, a metallic pressure vessel in the form of a thick-walled metallic vapor and liquid drum of large diameter, a multiplicity of downcomers distributed in a narrow zone extending longitudinally of the drum and joined to the drum at its lowermost part in pressure-tight relationship, the drum end portions extending longitudinally beyond the zone of the downcomers, a row of vapor generating tubular risers similarly joined with the drum in pressure-tight relationship at positions substantially circumferentially spaced from the row of downcomers, and conduit means within the drum forming tubular passages leading lengthwise of the drum from the projecting end portions of the drum into the inlets of the endmost downcomers, said conduit means establishing separate free flow of liquid from the drum end portions to the said endmost downcomers, the tubular passages formed by the conduit means being closed at their ends most remote from the end portions of the drum.

2. In a natural circulation vapor generating unit, a pressure vessel in the form of a cylindrical vapor and liquid drum having a large diameter and thick walls, a multiplicity of tubular downcomers distributed throughout a circumferentially narrow zone extending longitudinally of the midsection of the drum and joined to the

drum at its lowermost part in pressure-tight relationship, the end portions of the drum extending beyond the zone of the arrangement of downcomers, a row of tubular risers joined to the drum in pressure-tight relationship

- 5 at positions substantially circumferentially spaced from the zone of the downcomers, and conduit means of a tubular nature forming tubular passages leading longitudinally of the drum from the projecting end portions of the drum into the inlets of the endmost downcomers next adjacent the pertinent end portions, each of said conduit means covering the inlets of a plurality of downcomers, said conduit means establishing free flow of liquid from the drum ends to the said endmost downcomers.
- 10 15. 3. In a high pressure vapor generating unit, a pressure vessel in the form of a thick-walled metallic drum having hollow cylindrical straight mid-section and outwardly dished end portions at the ends of the mid-section, a furnace, means firing the furnace, vapor generating riser tubes subject to the heat of the furnace and joined with the drum in pressure-tight relationship thereto at levels above the level of the lowermost portion of the drum, a multiplicity of downcomer tubes distributed longitudinally of the mid-section of the drum and joined with the lower part of the drum in pressure-tight relationship, means establishing communication between the downcomers and the lower ends of the riser tubes, and means including a part of the drum wall between the inlets of downcomers nearest the end portions of the drum and forming conduits of a tubular nature disposed within the drum, each conduit leading from a space within a dished end portion of the drum to a plurality of inlets of the next adjacent downcomers, the conduits being closed at their ends remote from their ends within the dished end portions of the drum.

- 30 35. 4. In a high pressure vapor generating unit, a pressure vessel in the form of a thick-walled metallic drum having a straight hollow cylindrical main-section and outwardly dished sections closing the ends of the main-section, a furnace, means firing the furnace, vapor generating riser tubes subject to the heat of the furnace and joined in pressure-tight relationship with the drum at levels above the lowest level of the drum, a multiplicity of downcomer tubes having their upper ends joined with the lowermost part of the drum at positions longitudinally distributed throughout the main section of the drum and confined to a circumferentially narrow zone of the drum, means establishing communication between the downcomer tubes and the lower ends of the risers, and straight conduit means of a tubular nature disposed within the drum entirely below its normal water level and forming tubular passages leading from the spaces within the dished end portions of the drum to positions wherein each passage communicates with the inlets of the downcomers next adjacent the pertinent end portions, each tubular passage terminating inwardly in a closed end at a position remote from the midpoint of the drum length so as to leave the intermediate downcomers free of the conduit means, the conduit means having a free flow area greater than that of the downcomers directly associated therewith.
- 45 50 55 60

- 65 70 75. 5. In a high pressure vapor generating unit, a pressure vessel in the form of a thick-walled metallic drum having a straight hollow cylindrical mid-section and outwardly dished end portions at the ends of the mid-section, a furnace, means firing the furnace, vapor generating riser tubes subject to the heat of the furnace and having their upper ends joined with the drum in pressure-tight relationship thereto over portions of the drum at levels above the lowermost level of the drum, a plurality of downcomer tubes distributed in a narrow zone extending longitudinally of the drum mid-section and having their upper end joined with the lowermost part of the drum in pressure-tight relationship thereto, means

establishing communication between the downcomers and the lower ends of the riser tubes, and means including parts of the drum wall forming conduits of a tubular nature disposed within the drum and leading longitudinally of the drum from the spaces within the dished end portions of the drum to the inlets of the next adjacent downcomers, the conduits being closed at their ends most remote from the pertinent dished ends of the drum.
